Primary Examiner — Sheryl Lane*Assistant Examiner* — Mark T. Philpps(74) *Attorney, Agent, or Firm* — Cozen O'Connor(57) **CLAIM**

The ornamental design for a radiator for automotive applications, as shown and described.

DESCRIPTION

FIG. 1 is a front view of a radiator for automotive applications showing a new design;

FIG. 2 is a back view thereof;

FIG. 3 is a bottom view thereof;

FIG. 4 is a top view thereof;

FIG. 5 is an enlarged left view thereof;

FIG. 6 is an enlarged right view thereof; and,

FIG. 7 is a front perspective view thereof.

The broken lines in the drawing figures show portions of the radiator for automotive applications which form no part of the claimed design.

The shade lines in the figures show contour and not surface ornamentation.

1 Claim, 7 Drawing Sheets(56)
